RECORDING SYSTEM

Walter J. Albersheim, Great Neck, N. Y., assignor to Electrical Research Products, Inc., New York, N. Y., a corporation of Delaware

Application September 22, 1938, Serial No. 231,150

13 Claims. (Cl. 179—100.3)

This invention relates to systems for recording varying currents upon a photographic film and particularly to systems in which the recording point is shifted by current from a control circuit.

The object of the invention is a method and means of recording a larger range of amplitudes of the varying currents upon a photographic film within the normal track width.

A feature of the invention is a record materially narrower than the normal track width.

Another feature of the invention is a record of the varying currents compressed so that the amplitude or volume range of the record is less than the amplitude or volume range of the original currents.

A further feature of the invention is a record of constant width laterally displaced in the track in accordance with the degree of compression of the recorded currents.

Another feature of the invention is a reproducing system in which the quantity of light energy impressed on the photo-electric cell varies laterally of the record track.

These and other features of the invention will be apparent to those skilled in the art from the description set forth hereinafter, and from the accompanying drawing, in which:

Fig. 1 diagrammatically shows a manually controlled recording system;

Fig. 2 diagrammatically shows an automatically controlled recording system;

Fig. 3 diagrammatically shows the optical portion of the systems of Figs. 1 and 2;

Fig. 4 is an enlarged view of a portion of the film record;

Fig. 5 shows the mask used in the recording apparatus;

Fig. 6 diagrammatically shows a reproducing system; and

Fig. 7 shows the variation in light transmission across the scanning slit used in the reproducing system.

The microphone 1 represents the source of varying currents to be recorded. This source may be, as shown, a microphone actuated by acoustic waves, or any other source of varying currents such as a disc or film reproducer, a radio receiving set, a detector agitated by mechanical vibrations or any other electrical device actuated by any phenomenon to be recorded. The varying currents may be amplified in the amplifier 2, which may incorporate means for mixing the currents from two or more sources.

The range of amplitudes or volume of the varying currents is partially or completely compressed

by the compressor 3, which may be a lossy device such as a simple potentiometer or variable resistance network or a variable gain device such as a variable mu vacuum tube with a controllable grid bias.

The compressed currents may be further amplified in the amplifier 4 and supplied through the wires 5, 6 to a recording device 7, Fig. 3, conventionally represented as a two-ribbon variable density light valve. Any other known type of light valve may be used in place of the device shown, and the record may be of the variable density type or of the variable area type.

Light from a suitable source 8 is collected by the lens 9 and collimated by the lens 10 on a movable mask 11. The light passing through the aperture in the mask 11 is focussed by lens 12 on the recording device 7, which modulates the light in accordance with the currents in the wires 5, 6. The modulated light is focussed by the lens 13 upon the film. While one combination of optical elements has been shown and described it is apparent that many changes may be made in the optical system within the scope of the invention.

The control of the compressor 3 is linked to the control of the variable resistor 14. Current from the battery 15, flows through the variable resistor 14, and wires 16, 17 to the solenoid 18 attached to the movable mask 11. The mask 11 will be shifted a distance proportional to the movement of the controls 14 and 3, that is, proportional to the compression of the recorded currents. The spring 19 restores the mask 11 to its original position when the electromagnet 18 is deenergized.

The mask 11, shown in Fig. 5, has an aperture whose image on the film is materially narrower than the record track, and for a vertical movement of the mask 11 this aperture shifts from one side of the track to the other. The aperture may have straight sides inclined to the axis of the mask, so that the lateral shift is linearly proportional to the vertical movement, or the sides may be curved as shown in Fig. 5 to produce an arbitrary proportionality between the degree of compression and the lateral shift of the track.

In Fig. 2, the volume range is automatically compressed and the mask 11 automatically shifted by a circuit generally similar to the circuit disclosed in U. S. Patent 1,623,756 to C. F. Sacia. A part of the output of the mixer-amplifier 2 is amplified and rectified in the amplifier-rectifier 20, and the rectified output filtered by the low-pass filter 21. A part of the filtered output is supplied by wires 16, 17 to control the solenoid 18, and a

part controls the volume compressor 22 in circuit between the amplifier 2 and the recording device 1. Any suitable volume compressor may be used, such as the variable amplification device disclosed in the above patent to Sacia or the variable losser devices well known in the communication art.

In Fig. 4, the record 23 is of constant width and occupies materially less than the normal width of the track as indicated by the lines 24, 25. The record 23 is indicated as being shifted from one side of the track to the other. For convenience of illustration, this shift has been made much more rapid than would be desirable. In general, the shift is made quite slowly, rarely more than five times per second, and for sound of constant volume the record does not shift.

If the record is of the variable density, constant width type, the record may be continuously and proportionately shifted. With records of the variable area type, better results will be secured if the record is shifted in a series of steps. In such case the controls 3 and 14 may operate on terminals tapped off the resistors and the aperture in the mask 11 is cut in steps to correspond.

In Fig. 6, light from the source 26 is focussed by the lenses 27, 28 on a scanning slit in the plate 29. The scanning slit covers substantially the full width of the record track on the film 30, that is, the distance between the lines 24, 25 in Fig. 4. The light transmitted through the film excites the photoelectric cell 31 and produces a varying current which may be reproduced as sound; may operate a measuring device or signal; or may be applied to any other desired use. The volume range of the currents reproduced by such a simple system will of course be compressed and will lack contrast. To expand the volume range, the intensity of the light must vary laterally of the scanning slit as indicated in Fig. 7. This variation may be produced by an optical wedge or apertured screen 32 in the optical system, or by the optical stop disclosed in my copending application Serial No. 147,214, filed June 9, 1937.

The variation of intensity laterally of the scanning slit is related to the shape of the aperture in the mask 11, and may be linear or otherwise to correspond with the aperture. With a variable area record, the intensity will preferably vary in steps to correspond with the steps in the aperture of mask 11.

What is claimed is:

1. The method of recording sound which comprises exposing a light sensitive member to a light beam varied in accordance with the sound being recorded, reducing the range of the variations of said beam independently of variations in the volume of the sound and varying the lateral position of said beam with the volume of the sound.
2. The method of recording and reproducing sound which comprises exposing a light sensitive film to a light beam varied in accordance with the sound being recorded, reducing the range of the variations of said beam independently of variations in the volume of the sound, varying the lateral position of said beam with the reduction in range of the sound, developing and printing said film, scanning the print with a beam of light, exciting a light sensitive device with the light

modulated by said record, and varying the quantity of light impressed on said device laterally of the film in accordance with the lateral position of said record.

3. Apparatus for recording sound on a photographic film comprising means for converting sound waves into current variations, means for variably amplifying said variations, means responsive to said variations for controlling light impressed on said film, means for laterally shifting the area of said film exposed to said light, and a connection between said amplifying means and said shifting means whereby they operate simultaneously.

4. A film comprising a record of varying currents compressed in amplitude range, of constant width materially less than the width of the record track and laterally displaced in the record track in accordance with the degree of compression.

5. A film comprising a variable density sound record of constant width materially less than the width of the record track, laterally displaced in the record track in accordance with the volume.

6. A film record comprising a sound track in which the tone consists of a constant amplitude variable density record of constant width and the volume consists in a lateral displacement of said tone record.

7. The method of recording sound which comprises producing a record of the sound tone being recorded and laterally displacing said record in accordance with the volume variations of said sound.

8. The method of recording sound which comprises producing a variable density constant width record of the sound being recorded and laterally displacing said record in accordance with the average volume of said sound.

9. The method of recording sound which comprises producing a constant amplitude variable area record of the sound being recorded and varying the lateral position of said record in accordance with the amplification necessary to produce said constant amplitude.

10. The method of recording a varying electric current which comprises exposing a light sensitive member to a light beam varied in accordance with the varying electric current, reducing the range of the variations in said beam to less than the range of the variations in said current and varying the lateral position of said beam with the reduction in the range of variations in said current.

11. In combination, means for making a photographic record of a varying current and means comprising simultaneously actuated members for varying the amplitude of the recorded variations and the lateral position of the record.

12. In combination, means for making a photographic record of electrical variations and means actuated by said variations for varying the amplitude of the recorded variations and the lateral position of the record.

13. In combination, means for making a photographic record of electrical variations, and means actuated by said variations for compressing the amplitude range of the recorded variations and for laterally shifting the record.

WALTER J. ALBERSHEIM.
